UNITED STATES PATENT OFFICE.

CALEB K. COLBY, OF BROOKLYN, NEW YORK.

DESIGN FOR A WATCH-DIAL.

SPECIFICATION forming part of Design No. 23,464, dated July 17, 1894.

Application filed May 18, 1894. Serial No. 611,720. Term of patent 14 years.

To all whom it may concern:

Be it known that I, CALEB K. COLBY, a citizen of the United States, residing in Brooklyn, Kings county, New York, have invented and produced a new and original Design for a Watch-Dial, of which the following is a specification.

The design described herein relates to dials of watches and like time-pieces.

- 10 In the accompanying drawing forming a part of this specification the figure is a face view of my design as applied to a watch dial having a circular space for the usual time indicating characters.
- 15 The leading feature of my design consists in the minute graduation marks, *a*, arranged within the circle of space *b* for the time-indicating characters, and concentric therewith

throughout the major, upper portion of the main dial, *x*, and at the lower portion of said dial, said minute graduation marks arranged concentric with the minor, seconds dial, *z*, as seen at *a'*. Another feature of the design is the seconds graduation marks, *d*, on the minor dial *z*, arranged in a circle, and the space *e* for the seconds numerals, arranged in a circle exterior to the graduation marks *d*; all as shown in the accompanying drawing.

I claim as my invention—

The design for a watch-dial substantially as herein shown and described.

CALEB K. COLBY.

Witnesses:

HENRY CONNETT,
PETER A. ROSS.
